UNITED STATES PATENT OFFICE.

EDWIN H. STALEY, OF BURT, AND CHAUNCY I. MANSMITH, OF ALGONA, IOWA.

RAILWAY-CROSSING SIGNAL.

Application filed September 12, 1922. Serial No. 587,648.

To all whom it may concern:

Be it known that we, EDWIN H. STALEY and CHAUNCY I. MANSMITH, citizens of the United States, and residents of Burt and 5 Algona, respectively, in the county of Kosuth, State of Iowa, have invented a certain new and useful Railway-Crossing Signal, of which the following is a specification.

The object of our invention is to provide 10 a railway crossing signal of simple, durable and inexpensive construction that may be constructed without the use of expensive machinery, and by the use of materials readily obtainable in almost any community.

15 A further object is to provide a railway crossing signal in which when a train approaches the crossing from either direction it will, when at a certain predetermined distance from the crossing, automatically set 20 a signal to act as a warning to trains approaching the crossing; and

Further to automatically reset the switch to normal position when the train is at the crossing.

25 A further object is to provide a device of this class in which none of the parts of the operating device will be in any way injured or affected by the movement of the train in any direction; and

30 Further to provide a device of this class in which the movement imparted to the operating mechanism by the train will be slow and gradual, to thereby avoid excessive shocks and jars to the operating device.

35 Our invention consists in the construction, arrangement and combination of the various parts of the device, whereby the objects contemplated are attained, as hereinafter more fully set forth, pointed out in our claims, 40 and illustrated in the accompanying drawings, in which:

Figure 1 shows a plan view of a railway crossing having our improved signal device applied thereto.

45 Figure 2 shows a vertical sectional view on the line 2-2 of Figure 1.

Figure 3 shows a horizontal sectional view on the line 3-3 of Figure 2.

50 Figure 4 shows an enlarged sectional view on the line 4-4 of Figure 1.

Figure 5 shows a sectional view on the line 5-5 of Figure 1; and

Figure 6 shows a sectional view on the line 6-6 of Figure 3.

55 Referring to the accompanying drawings,

we have used the reference numeral 10 to indicate the rails of a railway track mounted upon the ties 11, and 12 indicates the rails of a cross track.

The signal proper comprises a stationary 60 support 13, in which is rotatively mounted a vertical shaft 14. At the top of the vertical shaft is the signal device 15 of any ordinary construction. In the lower end portion of the shaft 14 is a circular metal plate 65 16 fixed to rotate with the shaft 14, and provided at one side with shoulders 17 to be engaged by a stationary pin 18 to thereby limit the rotary movement of the plate 16.

On one edge of the plate 16 there is a 70 notch 19, and a pawl 20 is provided to engage said notch, which pawl is provided with a spring 21 for normally holding it toward the edge of the plate 16. There is also provided a rod 22 connected to the pawl where- 75 by it may be withdrawn from the notch.

Connected to one side of the center of the plate 16 is a contractile coil spring 23 so arranged as to normally hold the plate 16 to one limit of its movement, and on the opposite side of the center of the plate 16 is a rod 24 which, when pulled, will tend to rotate the plate 16 in opposition to the pull of the spring 23. This rod 24 is slidably mounted in a pin 25, which pin extends through 80 the plate 16 and has a head 26 below the plate so that the pin is free to rotate relative to the plate, as shown in Figure 6.

85 Mounted adjacent to the end of the rod 24 is a crank shaft 27 having a crank arm 90 28 at one end connected to the rod 24, and a crank 29 at the other end connected to a rod 30. This rod 30 is extended to a considerable distance along the side of the rails 10 in a direction away from the cross roads, 95 and its outer end is pivoted to a bell crank lever 31. A spring 32 is connected to the bell crank lever 31 to pull the rod 30 in a direction away from the signal device. Attached to the other end of the bell crank 100 lever 31 is a rod 33 which extends under the rail toward the center of the track.

Our improved device for actuating the rod 33 upon the approach of a train toward the cross tracks, and for permitting it to stand 105 still when the train is moving in an opposite direction, is as follows:

The reference numeral 34 indicates an actuating bar preferably mounted between the rails and extended substantially longitudi- 110

nally of the rails. This bar is provided at one end, as shown in Figure 4, with a lateral extension 35 slidably supported and having an upturned end 36. Fixed in position adjacent to the part 35 is a bracket 27 in which is mounted a rod 38, which rod slidably extends through the upright 36, and an extensible coil spring 29 is mounted on said rod.

By means of this arrangement it is obvious that the spring 39 normally holds the actuating bar 34 to its limit of movement adjacent to the stationary bracket 37, but that when pressure is applied to the side of the actuating bar 34 that is adjacent to the bracket 37, the actuating bar may move laterally in a direction away from the bracket 37.

At the other end of the actuating bar 34 there is a segmental arm 40 extending laterally and connected to the rod 33. This arm 40 is slidably mounted in a bracket 41. When the actuating bar 34 is in its normal position, as shown by solid lines in Figure 1, it is arranged on a line slightly divergent from the longitudinal line parallel to the track, but its end that is nearest the cross track may be moved laterally to the position shown by dotted lines in Figure 1, and when thus moved a pull will be exerted on the rod 33, and this pull will be in turn transmitted to the rod 34, which will cause the plate 16 to be rotated.

For actuating the bar 34 we preferably provide a downwardly extended lug 42 fixed to the cow catcher 43 of a locomotive or to any suitable part of a railway train. This lug has rounded corners so it will not catch or engage weeds or other things on the railway track. It is so positioned relative to the actuating bar 34 that when a train is approaching the cross tracks, as shown at the bottom of Figure 1, this lug 42 will engage the right side of the actuating bar 34, and then as the train progresses the actuating bar 34 will be swung toward the left, as shown by dotted lines at the bottom of Figure 1. When, however, the actuating lug 42 is moved in the opposite direction, that is to say, away from the cross tracks, then the lug upon approaching the actuating bar 34 will be in the position indicated by dotted lines at the bottom of Figure 1, and it will engage the left side of the actuating bar as shown and cause the upper end of the bar, as shown in said figure, to move toward the right, as illustrated in dotted lines in opposition to the spring 39, so that the lug may then pass beyond the actuating bar and over the part 35 thereof so that during such movement the rod 33 will not be actuated and the actuating bar 34 will not be in any way injured.

It is desirable that upon the train reaching a point adjacent to the cross tracks, the switch device will be reset to normal posi-

tion, and for accomplishing this purpose we have provided two metal bars 44 hinged together at their central portions at 45, and each provided at its outer end with a slot 46. Stationary pins 47 are extended through these slots to form guides. Connected to the adjacent ends of the bars 44 is the rod 22 connected to the pawl 20. When the pawl 20 is in the notch 19, then the bars 44 will assume the position shown by dotted lines in Figure 1. Then when the train approaches these bars from either direction, the lug 42 thereof will assume the position shown by dotted lines in Figure 1, adjacent to the said bars 44, and this lug 42 will slidably engage the face of the adjacent one of the bars 44 and move it toward the left, thus withdrawing the pawl 20 from the notch and permitting the spring 23 to actuate the signal. If the pawl is not in the notch, then the lug 42 may pass by without engaging the bars 44.

We have also provided an electric signal device for actuating a signal light as follows:

A stationary contact point 48 is provided on the signal device, and on the upright shaft 14 adjacent thereto is a coacting contact point 49, so that when the signal device is actuated in one direction, these contact points will engage, and when the signal device is actuated in the opposite direction they will disengage.

We have illustrated conventionally in Figure 3, the electric circuit comprising a battery 50 and a signal lamp 51, with the contact points 48 and 49 included in the circuit.

In practical use it is obvious that all of the parts of the device are of simple and inexpensive construction. We preferably locate the actuating lugs 42 near the center of the cow catcher, although it is obvious it could be located in other positions.

Assuming that a train approached the cross tracks from the position indicated by the cow catcher at the bottom of Figure 1, then the actuating lug 42 will engage the long actuating bar 34 and slide along it and push the bar 34 toward the left. This will cause a slight but positive action causing the bell crank lever 31 to pull upon the rod 30 to thereby rock the crank shaft 27 and pull upon the rod 24. This swings the plate 16 to position for setting the signal for the cross tracks. These movements are all positive, but will be relatively slow and there will be sufficient power applied to positively actuate the rod 30, even though it is of considerable length.

When the signal device has thus been moved to position, the pawl 20 will enter the notch 19, and this will lock the signal device in its position. When the train reaches the cross tracks, the bars 44 will be actuated

to release the pawl 20, and to permit the spring 23 to return the signal device to its normal position, and then when the train passes beyond the cross tracks, the actuating 5 lug 42 will move the actuating bar 34, as shown by dotted lines at the top of Figure 1, but this movement will not impart any motion to the signal device.

We claim as our invention:

10 1. In an improved railway crossing signal, the combination of a signal device, a rod extended substantially parallel with the railway track and connected with the signal device when a pull is exerted upon it, a signal actuating bar adjacent to the railway track and normally extended in a direction slightly divergent from a position parallel with the rails, one end being pivotally supported, the other end being free to swing laterally, 15 means whereby the lateral movement of the free end of the actuating bar will exert a pull on said rod, and means for yieldingly supporting the pivoted end of the actuating bar to permit lateral movement thereof, and 20 an actuating lug designed to be attached to a train for engagement with the actuating bar.

2. In an improved railway crossing signal, the combination of a signal device, a rod extended substantially parallel with the railway track and connected with the signal device when a pull is exerted upon it, a signal actuating bar adjacent to the railway track and normally extended in a direction slightly divergent from a position parallel with the rails, one end being pivotally supported, and the other end being free to swing laterally, means whereby the lateral movement of the free end of the actuating bar will exert a pull on said rod, means for yieldingly supporting the pivoted end of the actuating bar to permit lateral movement thereof, an actuating lug designed to be attached to a train for engagement with the actuating bar, spring actuated means for normally returning the signal device to normal position, a spring actuated pawl for locking it in normal position, two actuating bars pivoted at their adjacent ends and slidingly supported at their outer ends, and means for

connecting their inner ends to said pawl, for 50 the purpose stated.

3. In a device of the class described, an actuating bar formed with a lateral extension at one end, a stationary bracket and a spring device for normally holding the actuating bar against the stationary bracket, being capable of permitting it to be moved laterally away from the stationary bracket, and also forming a pivotal connection for the stationary bar to the bracket, said bar being 60 normally extended in a direction slightly divergent from a line parallel with the rails of a track, and means connected to the free end of the actuating bar for exerting a pull on a signal operating rod, for the purposes 65 stated.

4. In a device of the class described, an actuating bar formed with a lateral extension at one end, a stationary bracket and a spring device for normally holding the actuating 70 bar against the stationary bracket, being capable of permitting it to be moved laterally away from the stationary bracket, and also forming a pivotal connection for the stationary bar to the bracket, said bar 75 being normally extended in a direction slightly divergent from a line parallel with the rails of a track, means connected to the free end of the actuating bar for exerting a pull on a signal operating rod, said means 80 comprising a segmental arm on the actuating bar for the stationary bracket through which the segmental arm is slidingly extended.

5. In a signal device, the combination of 85 an upright shaft, a signal device thereon, a plate secured to the lower portion of the shaft, means for limiting the rotary movement of the plate, said plate being formed with a notch, a spring actuated pawl designed to enter said notch, a rod pivotally and slidingly connected to the plate at one side of its center, and a spring attached to the plate for returning it to normal position 90 after it has been moved by said rod. 95

Des Moines, Iowa, August 15, 1922.

EDWIN H. STALEY.
